METHOD OF REENFORCING BRIDGES

Arthur G. Leake, Bridgeport, Conn.

Application October 20, 1933, Serial No. 694,418

7 Claims. (Cl. 29—151)

This invention relates to new and useful improvements in methods of reenforcing or strengthening pin connected trusses or the like.

The invention has for an object to provide a simple and comparatively inexpensive method of reenforcing or strengthening pin connected bridge trusses or similar structures whereby bridges or other structures including such trusses may be strengthened for use for carrying much heavier loads than those for which the bridges were originally designed.

Another object is to provide a method as stated and which may be used or practiced to strengthen a bridge while the same is in use and without interfering with the usual traffic using the bridge.

A further object is to provide a method which does not require the building of false work to carry the joints of a bridge and which does not involve the building of a temporary truss or temporary trusses to support the load while the work of reenforcing the bridge is being done.

A still further object is to provide such a method which may be used where the available space or clearance is limited.

Other objects and advantages will become apparent from a consideration of the following detailed description taken in connection with the accompanying drawings wherein examples of the use of the method of the invention is shown. However, it will be understood that the invention is not limited to the details disclosed but includes all such variations and modifications as fall within the spirit of the invention and the scope of the appended claims.

In the drawings:

Fig. 1 is a side elevational view illustrating a portion of an I-bar bridge to be reenforced or strengthened by the method of the present invention;

Fig. 2 is a sectional view on an enlarged scale illustrating the method of anchoring or attaching reenforcing or strengthening members to a pin of the bottom chord of the bridge;

Fig. 3 is a similar view illustrating a slightly different arrangement which may be used for securing an end of a strengthening member or bar to an intermediate pin of the bottom chord of the bridge;

Fig. 4 is a similar view illustrating another arrangement;

Fig. 5 is a detailed sectional view illustrating the application of a pipe spacer;

Fig. 6 is a typical plan view showing the application of the reenforcing or strengthening

members to a pin of the bridge and showing the spacers in place;

Fig. 7 is a view similar to Fig. 4 but illustrating a slight variation;

Fig. 8 is a sectional view on an enlarged scale and illustrating the application of the method as the same is used in attaching or securing a diagonal reenforcing piece to a pin of the upper chord of the bridge;

Fig. 9 is a view similar to Fig. 8 illustrating a slight variation;

Fig. 10 is a similar view illustrating a further variation particularly as applied to the securing of the upper end portions of oppositely inclined diagonal strengthening members to the upper bridge chord; and

Fig. 11 is a view similar to Fig. 10 and showing a further slight variation.

Referring in detail to the drawings and at first particularly to Fig. 1, the bridge there shown is generally designated 15 and includes a top chord 16, a bottom chord 17 and vertical struts 18. In the present instance I am not particularly concerned with the upper chord 16, the present invention having particular relation to a method of strengthening or reenforcing the lower chord 17 and the applying of diagonal members 19 and 20. These diagonal members may be used to supplement or assist diagonal I-bars already in place or they may be applied in the absence of diagonal I-bars. The lower chord 17 includes I-bars 21 pivotally connected as by pins 22.

At the present time there are a large number of pin connected bridges in use and many of these bridges were built in a time when traffic was not nearly so heavy as at the present, and while such bridges were not designed to sustain the loads to which they are subjected the cost of their replacement is in many instances prohibitive. The present invention provides a method whereby these bridges may be strengthened and reenforced at comparatively little expense and without any interference with their normal use. According to the present invention additional load carrying members are incorporated in the lower chord of the bridge and new or additional diagonal members are applied to the bridge whereby its load carrying capacity is appreciably raised. In actual practice the reinforcements herein disclosed were designed to raise the load limit of the bridge from a 12 ton truck to a 30 ton truck.

To simplify the description the various pins 22 in the lower chord of the bridge have been designated A, B, and C. Fig. 2 illustrates the method of anchoring or securing the adjacent

ends of strengthening members or bars 23 to the pin A. According to the method as here disclosed, a plate 24 of the desired thickness and size is provided and through this plate there is drilled an opening of the size or diameter of the pin A and the plate is then split as by a saw, the cut extending through the drilled opening in the plate and dividing the plate into two sections. This cut may be along the line 25 and after the plate is cut it is assembled on the pin accommodating the pin in the above mentioned drilled opening.

The plate is preferably located approximately in the center of the truss and since the plate is divided or split as above explained the assembly of the plate on the pin is greatly facilitated. This is particularly true where the clearance is limited since the upper section of the plate may be slipped or worked into place over the pin and then the lower section welded to it giving proper alignment about the pin. Also, it will be apparent that the plate may be assembled on the pin without disturbing the I-bars pivoted to the pin and without the necessity for dismantling any portion of the bridge. The top section or portion of the plate is applied or located and then the lower section or portion is welded to it, the sections being welded together along the line on which they are cut as shown at 26.

To increase the bearing surface between the plate 24 and the pin A and to strengthen said plate blocks 27 are welded about their edges to the plate as at 28, one of these blocks being applied to each side of the plate. Each block is provided with an arcuate groove or recess 29 the surface of which groove or recess conforms to and engages the surface of the pin A. It will be noted that these blocks 27 are arranged to span the cut 25 at that side of the pin to which most of the stress will be applied. The adjacent ends of the strengthening members or bars 23 may now be welded to the plate 24 as at 30, it being noted that these bars are applied in such position that they span the welded joint between the sections of the plate and it will be understood that the end portions of the bars are applied one against each side of the plate.

If desired, bars 23 need not be applied to the plate 24 until after a plate 31 has been applied to the pin B since the opposite end portions of bars 23 are to be secured to such plate 31. Fig. 3 illustrates the method of applying plate 31 to the pin B and the method is substantially the same as that already described in connection with the application of plate 24 to the pin A. Plate 31 is of the desired thickness and is cut to the proper size to sustain the load which will be placed on it and an opening is then drilled in the plate, the opening being of the proper diameter to receive the pin B. Next, the plate is split or sawed as along the lines 32 and 33, the cuts entering the above mentioned drilled opening and extending from the opposite ends of the plate whereby the plate is divided into a pair of sections. The upper section is then assembled on the pin and the lower section welded to it along the lines of the cuts as at 34. This plate is also arranged approximately in the center of the truss so as to align with the plate 24.

Since the plate 31 is cut in two and then applied to the pin B it will be apparent that the plate may be easily applied without disassembling any parts of the bridge or other structure and that the sections of the plate may be worked

into place even though there is but small clearance. After this plate is in place the other ends of the bars or strengthening members 23 may be secured to it as by welding about the edges of said bars as 35. Attention is directed to the fact that these bars span the cut 33 and the bars are slightly spaced so that they receive the plate between them.

After one end of a bar 23 has been welded in place the bar is prestressed to the same unit stress as the old I-bars under dead load. This prestressing is accomplished by heating the bars 23 to expand them to the desired length according to the method described in my prior Patent No. 1,770,932 issued July 22, 1930, and then while these bars 23 are under stress or thus expanded, the other end is welded to the other plate at the next joint or pin 22. Thus, it will be seen that the bars are prestressed or expanded before they are welded at the second end and when they cool or return to normal temperature they immediately take up their share of the load.

Reinforcing or strengthening bars 36 extend between the pin B and the pin C and these bars are also slightly spaced apart so as to receive plate 31 between a pair of their end portions and such end portions are welded to said plate about the edges of the portions as at 37. These end portions of the bars overlap or straddle the welded cut 32 of the plate whereby they serve to additionally strengthen the plate. If it is desired that the plate have additional bearing surface on the pin then blocks similar to the blocks 27 may be applied to the plate.

Figs. 4, 5 and 6 illustrate the method of applying a plate 38 to the pin C, the said plate forming an anchoring or mounting means for the ends of the bars 36 remote from the plate 31. This plate 38 is of the desired shape, size and thickness and a hole of the diameter of the pin C is drilled through the plate and the plate is then sawed or otherwise cut from its opposite ends as at 39 and 40 each of said cuts entering the drilled opening. This, of course, divides the plate into a pair of sections and the upper section is worked into place on the pin C and the lower section is then welded to the upper section along the lines of cut 39 and 40 as at 41. Preferably, the plate 38 is arranged substantially in the center of the truss in alignment with the plates 24 and 31.

After the plate 38 has been mounted the ends of the bars 36 adjacent said plate are welded to the plate as at 42. Of course, these bars are slightly spaced apart so that they receive the plate between them and prior to the welding of the bars to the plate the bars are heated and expanded and are welded to the plate while so expanded so that on their return to normal temperature they will be prestressed. As shown, the bars overlap the cut 40 and if an additional bearing surface is required between the plate and pin, blocks, similar to the blocks 27, may be applied. Bars 43 are arranged in spaced relation so as to receive the plate 38 between them and end portions of these bars are welded to the plate as at 44 it being noted that the bars overlap or span the welded cut 39 of the plate.

Fig. 6 clearly shows the manner in which the plate 38 is arranged on the pin C. This figure is a typical plan view and discloses the arrangement by means of which the plates 24 and 31 heretofore described and other plates hereafter to be described are maintained in position approximately centrally of a truss. To accomplish

this split pipe spacers 45 are applied about the pin C at opposite sides of the plate 38 and the sections of the respective spacer are then welded together as along the lines 46.

5 It will be understood that the end portions of the bars 43 remote from the plate 38 are anchored or secured to the next pin of the bridge or other structure and it will further be understood that such bars are prestressed as described in my 10 above noted patent prior to the anchoring of the said other end portions. As shown in Figs. 4 and 7 the lower end portions of the added or additional diagonal members or bars 19 are welded to the plate 38 as at 47. These bars are arranged 15 in spaced relation so that they receive the plate between them and the upper end portions of these bars are secured or anchored as will later be described.

The strengthening or reenforcing members 20 20 as shown in Fig. 4 are not here shown as arranged in pairs but one such diagonal being disclosed and this diagonal has its lower end arranged to bear against an edge 48 of the plate 38 and said lower end is secured to the plate as by 25 a pair of short straps 49 arranged one at each side of the plate and welded to it as at 50. These short straps extend beyond the plate and receive the lower end of bar 20 between them and are welded to said bar as at 51. At its upper end 30 the bar 20 is secured or anchored as will later be described and it will be understood that the bars 19 and 20 are prestressed according to the method disclosed in my Patent No. 1,770,932 above referred to.

35 Fig. 7 discloses a slight variation of the method of Fig. 4 and where possible the same reference characters have been employed. The plate of Fig. 7 is not of the same configuration as plate 38 and is therefore given a new reference number being designated 52. This plate 52 is drilled and is then cut along the lines 39 and 40 and then welded together after being applied to the pin and has the end portions of the bars 36 and 43 welded to it as at 42 and 44 respectively. Also, 45 diagonal bars 19 are welded to the plate as at 41. The essential difference resides in the fact that diagonal bars 53 are substituted for the diagonal bar 20 of Fig. 4 and these bars 53 are slightly spaced apart so as to receive the plate between 50 their lower portions, such lower portions are welded to the plate as at 54. Of course, the upper ends of these bars 53 are suitably anchored and the bars are prestressed as above described and as disclosed in my patent previously referred to.

55 Figs. 8, 9, 10 and 11 illustrate several variations of the method as applied to the securing or anchoring of the upper ends of the diagonals to the pins of the top chord 16 of the bridge. Referring first to Fig. 8, the upper end portions of 60 the diagonal bars or strengthening members 19 are to be anchored to a pin 55 of the top chord of the bridge. To accomplish this, a plate 56 of the desired thickness, size and shape is provided and at the proper point is drilled to provide a hole of the diameter of the pin 55. Next, this plate is sawed or otherwise severed as along the lines 57 and 58, the said saw cuts extending from opposite ends of the plate and each entering the drilled opening whereby the plate is divided into 65 a pair of sections. These sections are worked in place on the pin 55 and are then welded along the lines of the cut as at 59.

The plate is located approximately in the center of the truss and it will be noted that owing 70 to the structure of the top chord there is very

little clearance. However, when the plate is cut in two it may be easily assembled on the pin and then welded together. This, of course, is accomplished without disconnecting or disassembling any of the bridge parts. To increase the 5 bearing surface between the plate 56 and the pin 55, blocks in the form of plates 60 may be welded against each side of the plate and each block or plate is provided with an arcuate recess 61, the curvature of the edge of which is the same as 10 that of the outer surface of the pin whereby the blocks bear against the pin.

It will be noted that the blocks 60 span the welded cut 58 of the plate and they therefore serve to strengthen the plate. After the plate 15 is in place the diagonal bars 19 are heated to expand them and then the upper ends of the bars are welded to the opposite sides of the plate as at 62 it being noted that such bars span the welded cut 57 of the plate. This last welding 20 operation takes place while the bars are heated and expanded so that they are prestressed on returning to normal temperature and immediately take up their share of the load.

Fig. 9 shows a slightly different arrangement 25 and in this figure the upper bridge chord pin is designated 63 and a plate applied to this pin is designated 64. Such plate has an opening drilled therethrough the opening being of the diameter of the pin and the plate is then sawed or otherwise 30 cut through from its opposite ends as along the lines 65 and 66, each cut entering the drilled opening. It will be noted that the lines of the cut 65 and 66 are arranged at an angle to one another but each cut entering the opening, the 35 plate is divided into two sections. With the plate divided into two sections the upper section may be hooked over or assembled on the pin and then the lower section may be welded to the upper section along the lines of cut as at 67. Owing to the 40 presence of the upper flange or plate of the top chord there is but slight clearance and the severing of the plate 63 makes possible its assembly on the pin without dismantling any of the bridge structure.

To increase the bearing surface between the plate and pin, blocks in the form of plates 68 may be welded against opposite sides of the plate, the weld being indicated at 69. Each of these blocks has an arcuate recess 70, the edge of which 50 is curved to embrace the pin. Preferably, these blocks are arranged in position spanning the welded cut 66 of the plate so as to strengthen the latter. The upper end portions of the diagonal bars or strengthening members 19 receive the 55 plate 64 between them and these upper end portions are welded to the plate as at 71 and span the welded cut 66 of the plate to strengthen the same. After one end portion of each of these members 19 has been anchored, the member is 60 heated to expand it and while it is so expanded its other end portion is anchored whereby when the member returns to normal temperature it is prestressed and immediately assumes part of the load.

65 Referring now to Fig. 10, the pin of the top chord of the bridge is designated 72 and has applied to it a plate 73 said plate being somewhat L-shaped and arranged on the pin at a point approximately in the center of the truss. 70 An opening of the diameter of the pin 72 is drilled through the plate 73 substantially at the juncture of the arms of the plate and then the plate is cut to divide it into upper and lower sections. The lines of cut are indicated at 74 and 75.

75 and are through the plate from the outer ends of its arms and each cut enters the drilled opening. Next, the upper section of the plate is worked into position over the pin and then 5 the plate sections are welded together along the lines of the cuts as at 76.

After the plate is in position, the upper end of a diagonal bar 20 may be anchored to one of the arms of the plate as by means of short pieces 10 or straps 71 welded one to each side of the upper end portion of the bar, such straps projecting beyond the end of the bar and receiving a portion of the plate between them. When the bar has been heated to expand it the projecting ends 15 of the pieces 71 are welded to the plate as at 78, the said pieces spanning the welded cut 75 of the plate. To the other arm of the plate the upper end portion of bars or strengthening members 19 may be secured. Said upper end portions 20 receive the other arm of the plate between them and after being heated so that they are expanded to the desired extent they are welded to the plate at at 79. These welded portions of the bars 19 span the welded cuts 74.

25 Fig. 11 shows a slight variation of the arrangement of Fig. 10 and where the parts are the same the same reference characters have been employed. According to Fig. 11 after the plate 73 is in position the upper end portions of diagonal bars or strengthening members 80 are secured to the respective arms of the plate. The upper end portion of each bar 80 is shown as abutting the outer end of one arm of the L-shaped blade and a short piece or strap 81 is welded to each 30 side of the upper end portion of each of the bars 80, the weld being indicated at 82. These pieces project beyond the ends of the bars so that each arm of the plate has its end portion received between a pair of the pieces 81 and after the 35 bars are expanded the said projecting end portions of the pieces are welded to the plate at 83 this welding operation being performed while the bars are expanded so that when they return to normal temperature they are prestressed and 40 immediately assume part of the load.

45 From the foregoing description taken in connection with the accompanying drawings it will be apparent that according to the method of the present invention a pin connected bridge may 50 at comparatively little expense be strengthened or reenforced so as to very appreciably raise its load carrying limit. Additional bars may readily be incorporated in the bottom bridge chord and additional diagonal bars may be added. 55 Owing to the prestressing of the new bars they immediately assume their proper share of the load.

60 Owing to the fact that the various plates are cut in two after being drilled the plates may be readily positioned on the bridge pins even though there is but small clearance. Further, this step enables the operator to mount the plates on pins without disconnecting the I-bars already connected with the pins. Of course, blocks similar 65 to the blocks 27 of Fig. 2 and 60 of Fig. 8 may be added to the other plates when it is desired to provide additional bearing surface between the plates and pins. The spacers 45 are used in each instance to maintain the plates properly 70 located approximately centrally of the trusses and it will be apparent from Fig. 6 that the addition of the plates and the strengthening members or bars does not require the removal of the original I-bars 21. Also, it will be understood 75 that the various diagonals may be connected

with the plates according to any of the disclosures since it is not necessary to connect any particular diagonal in any particular way. That is, the end portions of the diagonals may overlap the plates as in Fig. 8 or they may abut the 5 plates and be spliced to them as in Fig. 11.

Having thus set forth the nature of my invention, what I claim is:

1. The method of strengthening pin connected trusses while in position in a fabricated structure, the same comprising providing a plate, forming a hole in said plate to receive a pin, splitting said plate into two sections by a cut passing through said hole, assembling the separate plate sections about the pin while it is in 10 position in the structure and with the pin disposed through said hole, then welding the sections of the plate together along the line of said cut, and then securing an end of a strengthening bar to the plate. 15

2. The method of strengthening pin connected trusses while in position in a fabricated structure, the same comprising providing a plate, forming a hole in said plate to receive a pin, splitting said plate into two sections by a cut passing 20 through said hole, assembling the separate plate sections about the pin while it is in position in the structure and with the pin disposed through said hole, welding the sections of the plate together along the line of said cut, providing a 25 block having an arcuate recess in one of its edges, securing said block to said plate with the edge of the recess in alignment with a portion of the edge of the hole in the plate whereby said block also engages the pin, and then securing 30 an end of a strengthening bar to the plate. 35

3. The method of strengthening pin connected trusses while in position in a fabricated structure, the same comprising providing a plate, forming a hole in said plate to receive a pin, splitting said plate into two sections by a cut 40 passing through said hole, assembling the separate plate sections about the pin while it is in position in the structure and with the pin disposed through said hole and with the plate located approximately in the center of the truss, welding the sections of the plate together along the line of said cut, disposing the sections of a split pipe spacer about the pin at each side of 45 the plate, securing together the sections of the respective spacers, and then anchoring one end 50 of a strengthening bar to the plate. 55

4. The method of strengthening pin connected trusses while in position in a fabricated structure, the same comprising providing a plate, forming a hole in said plate to receive a pin, splitting said plate into two sections by a cut passing 60 through said hole, assembling the separate plate sections about the pin while it is in position in the structure and with the pin disposed through 65 said hole, welding the sections of the plate together along the line of said cut, arranging a strengthening bar with one of its end portions overlapping said plate, and then welding said end portion to the plate. 70

5. The method of strengthening pin connected trusses while in position in a fabricated structure, the same comprising providing a plate, forming a hole in said plate to receive a pin, splitting said plate into two sections by a cut 75 passing through said hole, assembling the separate plate sections about the pin while it is in position in the structure and with the pin disposed through said hole, welding the sections of the 80

the plate together along the line of said cut, arranging a strengthening bar with one of its end portions abutting an edge of the plate, and then welding a splice plate to said end portion and to the plate.

- 5 6. In a method of strengthening pin connected trusses while they are in position in the structure, the steps which comprise placing about the pin 10 while it is in position in the structure a plate comprising two separate complementary sections having notches in adjacent edges adapted to be placed in alignment to form an opening for the pin and with the pin in this opening, then 15 welding the adjacent edges of the sections to-

gether, and welding the end of a strengthening bar to the plate.

7. The method of strengthening pin connected trusses while they are in position in the structure, comprising placing about each of two spaced pins while they are in position in the structure a plate comprising two separate complementary sections having notches in adjacent edges adapted to be placed in alignment to form an opening for the pin and with the pins in these openings, 10 then welding the two sections of the plate together to form a unitary plate, and welding strengthening bars to the respective plates to connect them together.

5
